UNITED STATES PATENT OFFICE.

ALDIS O. MORGAN, OF HERMON, NEW YORK.

STAKE-AND-RAIL FENCE.

SPECIFICATION forming part of Letters Patent No. 394,874, dated December 18, 1888.

Application filed March 2, 1888. Serial No. 266,001. (No model.)

To all whom it may concern:

Be it known that I, ALDIS O. MORGAN, a citizen of the United States, and a resident of Hermon, St. Lawrence county, and State of New York, have invented a new and useful Fence, of which the following is a specification.

The nature of my improvement consists in a straight farm-fence which is exceedingly simple and inexpensive in construction, durable in use, and yet strong, as will be herein-after specified, and more particularly pointed out in the claims.

My improvement is shown in the accompanying drawings, to which reference is made, and which forms a part of this description, in which like letters and characters refer to similar parts, and in which—

Figure 1 is a perspective view of a fence built in accordance with my invention, and Fig. 2 is a vertical cross-section thereof.

I will now proceed to describe my improvement in such full, clear, and exact terms that any one skilled in the art to which the invention appertains will be able to make, construct, build, and use the same.

In setting up my fence I ordinarily make use of a series of temporary supports or blocks, (not shown in the drawings,) one at each end of the rails F, which blocks are advantageously short pieces of board or plank about twenty-eight or thirty inches long and lightly driven into the earth at their lower ends. On these boards or blocks as a scaffold I place two or more of the line of rails, F, and drive a pair of stakes, A and C, of unequal length, firmly into the ground at an angle across the top of the said rails near each end, these two stakes being substantially in a vertical plane at a right angle to the length of the fence. In the fork or crotch made by the crossing of these stakes I lay the upper rail, E, of the panel. I then drive securely into the ground the vertical post or stake B, causing the same to rest in direct contact with the two rails F and E, already placed, and also in direct contact with one of the crossed stakes, preferably the longer, (marked A.) It is also preferred for strength and durability that the vertical stake be always set on the same side of the series of cross-stakes in the line where the adjacent panels meet. When I have brought the ends of the rails F and E of these

adjacent panels together, as shown in the drawings, and settled them snugly into their seats in both the upper and under crotches or forks of the crossed stakes, I preferably cut a light gain or notch, b, in the vertical post B just above the level of the rail E. Into this notch I draw a wire, I, and pass one end of it on and about the stake A and around the stake C, where its end is intertwined with the remaining end of the wire drawn down from the notch across the top of the rail E. The wire I thus firmly binds together the rail E and the three stakes A B C at their several points of contact, making a broad, strong, and solid abutment at the end of every panel in the fence. I then place the top rails, D, in the fork made by the vertical stake B and the inclined stake A, and, having snugly seated them therein, proceed to fasten the wire K to the upper extremity of the inclined stake. I then draw the free end of the wire K down over the top rails, D, thus seated in the fork of the stakes, and over the ends of the rails E, resting in the upper fork of the inclined stakes and on under fork of these same stakes. I then draw the free end of the wire K tightly about the short stake C, nearly opposite the line of rails F, and securely fasten the same to the said stake. This also binds the three rails of each extremity of any two adjacent panels firmly together and to the three stakes where the extremities of the panels come together. The temporary supports or blocks upon which the rails F have rested are now withdrawn and other panels of the fence are put up. The bottom rails, G, of the fence are now secured by a short bight of wire, M, to the lower end of the longer stakes, A, near the ground.

To prevent any possible longitudinal collapse of the fence as above constructed, I provide a pair of brace-rails, H, in adjacent panels, as shown. One end of each brace-rail of the pair is fitted to bear against the top of the vertical stake B. The other end of the pair is made to bear against the bottom or lower end of the two adjoining vertical stakes B. So firm and durable is the fence, however, made as hereinabove described, that while the fence extends in a perfectly straight line it is found in practice to be unnecessary that every panel should be braced against

longitudinal collapse. A brace at every six or eight rods in the line of the fence is found to be quite sufficient.

It will be observed (see Fig. 2 of the drawings) that the fence herein described does not maintain a vertical position—that is to say, the rails comprising the several panels do not rest one directly over the other, as in ordinary fences. On the contrary, the bottom rail, M, and the top rail, D, with the rails that are intermediate, are in a plane which is inclined in quite an angle less than a right angle to the surface of the ground upon which the fence stands. This feature I estimate as of much value in a fence of the character described. An animal is turned by a fence not alone by its height, but by its difficulty to overcome. A broad barrier is effectual to turn an unruly animal, whereas often a merely high one is ineffectual to restrain it.

In my fence an animal coming up with an intent to vault over finds itself hindered upon either side before it reaches the actual difficulty. On the one side the bottom rail, M, prevents the animal from getting its nose over the top rail. On the other side it can get its nose over, but only to see the broad barrier ahead, beyond which it must leap before it can clear the fence, and it is well known that most domestic animals will not ordinarily undertake to vault a fence which they do not feel able to effectually clear.

Having now, therefore, fully ascertained and set forth my improvement, what I claim, and desire to secure by Letters Patent of the 35 United States, is—

1. The fence herein described, comprising a panel having a pair of crossed stakes at each end, a rail resting in the crotches thereof, a vertical stake provided with a gain or cut, as 40 described, in contact with the rail and the said crossed stakes, and a bight of wire passing within the said gain or cut in the vertical stake and around the crossed stakes and the rail to secure the same firmly together, as set 45 forth.

2. The fence herein described, comprising a panel having a pair of crossed stakes at each end, two rails resting the one in the upper and the other in the under or lower crotches thereof, a vertical stake in contact with the said rails and the said crossed stakes, a bight of wire securing the said stakes and upper rails securely together, a third rail resting in the crotches made by the vertical stakes and one 50 of the crossed stakes of each pair, and a supplemental bight of wire securing the said third rail, the stakes, and the first and second rails firmly together, as set forth.

ALDIS O. MORGAN.
